The ornamental design for a shade device, as shown and described.

DESCRIPTION

A portion of the disclosure of this patent document contains material which is subject to intellectual property rights such as but not limited to copyright, trademark, and/or trade dress protection. The owner has no objection to the facsimile reproduction by anyone of the patent document or the patent disclosure as it appears in the Patent and Trademark Office patent files or records but otherwise reserves all rights whatsoever. This application is being filed on Nov. 15, 2011 on the same date that another application entitled "Shade Device" to Allen L. Beachy is being filed.

FIG. 1 is a top perspective view of the present invention;

FIG. 2 is a bottom perspective thereof;

FIG. 3 is a top view thereof;

FIG. 4 is a bottom view thereof;

FIG. 5 is a right side view thereof, the left side view being a mirror image of the right side view;

FIG. 6 is a front view thereof, the rear view being a mirror image of the front view; and,

FIG. 7 is an environmental view thereof.

The breaks in the drawing figures show no specific length. In the drawings, the broken lines depict portions of the shade device that form no part of the claim.
